P. W. ACKERMANN

EMBROIDERED LACE MEDALLION

Filed April 25, 1928

Paul W. Ackermann

INVENTOR

UNITED STATES PATENT OFFICE.

PAUL W. ACKERMANN, OF NORTH BERGEN, NEW JERSEY.

DESIGN FOR AN EMBROIDERED LACE MEDALLION.

Application filed April 25, 1928. Serial No. 26,462. Term of patent 3½ years.

To all whom it may concern:

Be it known that I, PAUL W. ACKERMANN, a citizen of the United States of America, residing at North Bergen, the county of Hudson, and State of New Jersey, have invented a new, original, and ornamental Design for Embroidered Lace Medallion, of which the following is a specification, reference being had to be accompanying drawing, forming part thereof.

The figure is a plan view of the embroidered lace medallion showing my design.

I claim:

The ornamental design for embroidered lace medallion, as shown.

PAUL W. ACKERMANN.
